BILLFOLD WITH GUSSET POCKET

Roe P. Henderson, Springfield, Ohio, assignor to
The Springfield Leather Products Co., Springfield, Ohio, a corporation of Ohio

Application October 16, 1944, Serial No. 558,789

2 Claims. (Cl. 150—38)

1

This invention relates to pocket wallets or billfolds.

An object of the invention is to provide an improved construction of pocket wallets or billfolds that permit more freedom of insertion of paper bills into the bill pockets of the wallet, and which also provide a larger space to receive a greater number of paper bills.

Another object of the invention is to provide a pocket wallet having a bill receiving compartment that is provided with expansible end walls to permit expansion of the bill compartment for receiving a large number of bills.

Another object of the invention is to provide a pocket wallet with expansible end walls of the bill receiving compartment that are constructed and arranged in a manner that the excess material in the expansible end walls is always positioned inwardly of the bill compartment.

A still further object of the invention is to provide a pocket wallet in accordance with any of the foregoing objects wherein the end walls of the bill receiving compartment comprise a gusset, wherein an intermediate partitioning wall is placed in the bill receiving compartment in engagement with the gusset end walls of the bill receiving compartment to retain the gusset end walls inwardly of the bill receiving compartment whenever the wallet is folded.

Another object of the invention is to provide a pocket wallet in accordance with any of the foregoing objects wherein the intermediate partitioning wall in the bill receiving compartment is free to move longitudinally in the bill receiving compartment, but which is attached to the gusset end walls of the bill receiving compartment in such a manner as to pull the gusset end walls inwardly of the bill receiving compartment whenever the wallet is folded.

Further objects and advantages will become apparent from the drawings and the following description.

In the drawings:

Figure 1 is a perspective elevational view of a pocket wallet involving features of this invention.

Figure 2 is a horizontal cross-sectional view of the pocket wallet.

Figure 3 is a vertical cross-sectional view of the pocket wallet taken along line 3—3 of Figure 2.

Figure 4 is a fragmentary elevational view of a modified construction of the pocket wallet.

In this invention the pocket wallet or billfold consists of a front wall 10 of a height and length that establishes the external dimensions of the

2

billfold. A rear wall 11 consists of two sections 12 and 13 that may be integral with the front wall section 10 and be folded along the bottom edge 14 of the front wall section 10 or the sections 12 and 13 may be stitched to the front wall section along the bottom edge 14 thereof to thereby place the rear wall sections 12 and 13 upon the rear face of the front wall section 10.

The rear wall section 13 has a section 15 that may be integral therewith folded along the fold line 16 or may be stitched thereto to lay against the inside face of the rear wall section 13, thus forming a tubular structure that receives one end of a bridging wall 17 that extends between the rear wall section 13 and the enclosing wall section.

The rear wall section 12 is provided with a similarly constructed wall section 18 that encloses the opposite end of the bridging wall 17.

The front wall section 10 and the rear wall section 12 are connected together at the left-hand ends thereof by a gusset wall 20 that is in the general shape of a V-shaped wall. The gusset wall 20 has one edge thereof secured to the edge 21 of the front wall section 10 by any suitable means such as the row of stitching 22. The opposite edge of the gusset wall 20 is attached to the rear wall section 12 by any suitable means such as the row of stitching 23. It will be noted that the gusset wall 20 is disposed in such a manner between the front wall 10 and the rear wall 11 that the apex of the V-shaped gusset wall extends inwardly of the bill compartment formed by the space between the front wall 10 and the rear wall 11 composed of the sections 12 and 13.

The opposite end of the billfold is provided with a gusset wall 25 constructed in a manner similar to the gusset wall 20 and having one edge thereof secured to the front wall 10 by the row of stitching 26, and the opposite edge thereof secured to the rear wall section 13 by the row of stitching 27. The degree of opening of the space between the front wall 10 and the rear wall 11, particularly at the ends of the bill compartment, is thus greatly increased by the use of the gussets 20 and 25 to permit a more free insertion of bills into the bill receiving compartment 28. With the gussets folded inwardly of the bill receiving compartment as illustrated in Figure 2, they will normally tend to return to the position illustrated whenever the walls of the billfold are collapsed upon one another. This is particularly true in view of the fact that the gusset walls 20 and 25 extend downwardly to the bottom of the billfold.

between the front wall 10 and the rear wall sections 12 and 13 as represented by the fold edge 14 of the billfold. This is quite apparent from the sectional view of Figure 3 showing the gusset walls adjacent the fold edge 14 of the billfold.

To partition the bill receiving compartment 28, an intermediate partitioning wall 30 is disposed between the front wall 10 and the rear wall 11. This partitioning wall 30 is provided with an extension 31 on one end thereof that passes through a slot 32 provided in the apex of the V-shaped gusset wall 20. The extension 31 is provided with outwardly extending ears 33 which prevent the extension 31 from being readily removed from the slot 32 because the ears 33 will engage the solid portion of the gusset wall 20 at opposite ends of the slot 32.

A similar extension 34 is provided on the opposite end of the partitioning wall 30 and has ears 35 that prevent the extension 34 from being removed from the slot 36 provided in the apex of the V-shaped gusset wall 25.

With the billfold or wallet in flat condition as illustrated in Figures 2 and 3, it will be noted that when the ears 35 on the partitioning wall 30 are positioned against the apex of the gusset wall 25 that the ears 33 on the opposite end of the partitioning wall 30 are spaced a substantial distance from the apex of the gusset wall 20, thereby allowing certain freedom of movement of the partitioning wall 30 longitudinally in the bill receiving compartment 28. However, it will also be noted that the relationship of position of the ears 33 and 35 on the partitioning wall 30 are such that the gusset walls 20 and 25 cannot move outwardly beyond the end edge of the front wall 10 without striking the ears 33 and 35. The arrangement is such that the ears 33 and 35 always tend to retain the gusset walls 20 and 25 inwardly of the bill receiving compartment 28, so that when the billfold or wallet is folded along a center line between the ends thereof the gusset walls 20 and 25 will be prevented from bending outwardly of the bill receiving compartment 28. The ears 33 and 35 on the intermediate partitioning wall 30 thus act as a restraining or confining means for preventing outward folding of the gusset walls 20 and 25 relative to the bill receiving compartment 28. It will also be noted that the length of the intermediate partitioning wall 30 is such that when the ears 35 engage the gusset wall 25, the opposite end of the partitioning wall 30 does not extend beyond the edge of the front wall 10, thus the ends of the intermediate partitioning wall represented between the extensions 31 and 34 will not protrude beyond the ends of the billfold at any time either when the billfold is in flat condition or when folded.

The rear wall section 13 of the billfold may be provided with a coin pocket 40 consisting of a front wall having a section 41 attached to a section 43 by a gusset 42 so as to provide for expansibility of the pocket 40. The section 43 of the front wall is secured to the rear wall section 13 by rows of stitching 44 at opposite ends thereof. A cover flap 45 is secured to the rear wall section 13 and folds over the upper edge of the front wall 41 to close the top portion of the coin pocket 40 and is provided with a snap lock 46.

In Figure 4 there is shown a modified construction of a billfold similar in construction to the one described but with an additional feature

consisting of a flap 50 integral with or attached to the front wall 10 and folding over section 30 in order to provide concealment of bills or other papers when placed between section 30 and front wall 10. This flap is not attached to section 30 so that the lateral movement of section 30 is not restrained by this alternate construction.

While the device disclosed and described herein constitutes a preferred form of the invention yet it will be understood the device is capable of alteration without departing from the spirit of the invention, and that all modifications that fall within the scope of the appended claims are intended to be included herein.

Having thus fully described my invention, what I claim as new and desire to secure by Letters Patent is:

1. A billfold comprising, a front wall, a rear wall, gusset end walls V-shaped in transverse cross-section having opposite edges thereof secured to said front wall and said rear wall, one of said gusset end walls being positioned in each end of the billfold with the apex of the gusset end wall disposed inwardly of the bill receiving compartment formed between the front wall and the rear wall, a partitioning wall disposed in the bill receiving compartment and connected to said gusset end walls along the apices thereof, and means extending from said partitioning wall through the apex of at least one of said gusset end walls and having means thereon to regulate the maximum outward extension of the gusset walls and thereby prevent the same from extending beyond the end edges of the billfold.
2. A billfold comprising, a front wall, a rear wall, gusset end walls V-shaped in transverse cross-section having opposite edges thereof secured to said front wall and said rear wall, one of said gusset end walls being positioned in each end of the billfold with the apex of the gusset end wall disposed inwardly of the bill receiving compartment formed between the front wall and the rear wall, the apex of each gusset end wall being formed with a slot, a partitioning wall disposed in said bill receiving compartment, and a T-shaped extension at each end of said partitioning wall and received in the slot of the respective gusset end wall, the width of the narrow part of said extension in the direction of its receiving slot in the gusset wall being narrower than the length of said slot and the wide part of said extension being wider than said slot.
